LABEL PASTING MACHINE

Joseph Ettl, Plainfield, N. J., assignor to Potdevin
Machine Company, Brooklyn, N. Y., a corpora-
tion of New York

Application April 29, 1931, Serial No. 533,646

3 Claims. (Cl. 271—39)

This invention is directed to an improvement in label pasting machines, and has for one of its objects the provision of a machine which is motor driven and of improved construction as compared to existing machines, means being provided whereby the labels are fed automatically from a stack and whereby the amount of glue or paste applied to the labels can be readily regulated. I provide also for certain adjustments of the machine whereby the same will accommodate labels of different sizes.

In the drawings:

Fig. 1 is an elevational view partly in section of an embodiment of my invention;

Fig. 2 is a plan view; and

Fig. 3 is a section taken substantially on the line 3—3 of Fig. 1.

Referring to the drawings in detail the labels to which glue or paste is to be applied are stacked upon a vertically movable table 1. Such a stack of labels is shown at 2 in Fig. 1.

The table 1 is suspended from vertically extending rack posts 3, these racks passing through sleeves 4 forming part of the machine frame. 25 5 is a shaft extending transversely of the machine and carrying pinions 6 meshing with the racks 3.

At one end the shaft 5 is provided with a flat coil spring 7 one end of which is attached to the shaft and the other end to one of the sleeves 4. 30 The spring is so wound on the shaft that it constantly exerts a rotative action on shaft 5 in a direction to lift the racks 3 and platform or table 1.

Extending across the machine above the shaft 5 and secured to the machine frame by screws 8 are two flat plates 9 slightly spaced apart. Above these plates and resting thereon is a pair of plates 10 extending lengthwise of the machine. These plates are slotted on their underside so as to receive the transverse plates 9 and to be guided thereby. Suspended from each of these plates is a plurality of vertically extending posts or rods 11 which pass downwardly through transverse slots 12 in the table or platform 1.

45 A designates a bolt which passes through each of the plates 10 and into the space between the transverse guiding plates 9, the bolts being squared as shown at B so as not to turn in the slot provided by the spacing of the two members 9. By loosening the nut C with which this bolt is provided it will be obvious that the members 10 may be moved bodily transversely of the machine to move the rods 11 transversely. These rods are guiding rods and are adapted to engage 50 the sides of the stack of labels 2. By providing

this adjustable construction it is obvious that the machine may accommodate labels of different widths.

13 designates a stationary vertically extending plate or stop mounted on the frame of the machine adjacent the forward end of the table or platform 1, and against which the labels are pushed in stacking.

Extending transversely of the machine above and adjacent the forward end of the plate 1 is a shaft 14 mounted in suitable bearings in the machine frame. This shaft passes through a rockable sleeve 15. The shaft also carries a feed roller 16 loose thereon. One end of the shaft 14 extends outside the frame of the machine and carries a sprocket 17 for a chain 18 the other end of which is mounted on a sprocket 19 on a transverse shaft 20, passing through a sleeve 21 rigid with sleeve 15.

The shaft 14 also carries a gear 22 meshing with 75 an intermediate gear 23 in mesh with a gear 24 on a transverse shaft 25, the latter carrying a pulley 26 for a belt 27, the other end of which is carried by a pulley 28 for the gluing mechanism. The shaft 25 also carries a large pulley 80 29 for the motor driven belt 30. The motor is designated 31.

Below the shaft 25 is a shaft 32 carrying a plurality of rollers 33 and 34. These rollers cooperate with the roller 16 for transferring the labels 85 from the stack 2 and advancing them through the machine as will be pointed out.

On the shaft 14 adjacent the roller 16 is a sleeve 35 provided with spaced annular flanges 36 adjacent one end thereof. This sleeve 35 is provided 90 with a key 37 pinned thereto, as shown at 38 in Fig. 3, and engaging a slot 39 in the shaft.

The end of the roller 16 which faces the sleeve 35 is provided with a flange 40 while the sleeve 35 is provided with a similar flange 41. The flange 95 41 carries pins 42 each provided with a spring, these pins at their outer ends carrying a friction disc 41' adapted to engage the flange 40. This provides for a flexible drive connection between 100 sleeve 35 and roller 16.

The shaft 32 above referred to and which carries the rollers 33 and 34 is hollow throughout part of its length and receives a pin 43 backed by a spring 44, the function of this spring being to maintain the pin in an outward position. The wall of the hollow part of the shaft 32 is provided with a slot 45 which receives one end of a yoke 46 attached to the rod or pin 43 in any suitable fashion. The yoke 46 extends upwardly as seen in 110

Figs. 1 and 3 and engages the sleeve 35 between the flanges 36.

- Pivoted on the lower part of the machine frame at 47 is an arm 48 extending upwardly in front of the outer end of the pin or rod 43. This lever below its pivot is provided with an extension or tail 49 adapted to be engaged by a cam 50 mounted on a shaft 51 carried by the frame of the machine and which shaft carries a hand crank 52. 5
- 10 Rotation of this crank will cause the cam 50 to force the tail 49 of the lever or arm 48 outwardly against the action of a spring 53 moving the upper end of the lever inwardly to force the rod or pin 43 inwardly and hence move the sleeve 36 15 to the left, as viewed in Fig. 3, permitting the key 37 to engage the slot 39 in the shaft 14 to couple the sleeve 35 and hence roller 16 to the shaft.

Beyond the rollers 33 and 34 and substantially in line with the top thereof is a plate 54 which is 20 adapted to receive the labels as they are fed forward from the stack 2 and pass along this plate to be picked up by a roller 55 on sleeve 21 and a small roller 56 mounted at the underside of plate 54. The plate 54 constitutes the cover plate for 25 a glue pot G.

The glue pot G also mounts a gluing roller 57. This roller is mounted on a shaft 58 provided at its outer end with a gear 59, meshing with pinions 60 and 61 on the outer ends of the shafts for 30 guide rollers 62 and 63, respectively. The shaft for the guide roller 63 carries at its other end the driven pulley 28 already referred to. This provides a drive for the gluing roller 57 as well as for the rollers 62 and 63.

35 64 designates a series of stripper fingers pivoted at 65 mounted above the gluing roller and adapted to strip the labels therefrom.

In operation it will be seen that rotation of the motor 31 will drive the large pulley 29 and through 40 the gears 24, 23 and 22 rotate the shaft 14. It will be seen also that rotation of shaft 14 will drive feed roller 55. At the same time through the driving mechanism above described the gluing roller will be driven as well as guide rollers 62 and 45 63. When labels are to be fed from stack 2 the hand crank 52 is operated into position to depress pin 43 and through the yoke 46 etc. establish a driving connection between shaft 14 and feed roller 16. As each label is removed from the stack 50 the stack automatically raises through the action of the spring 7. The uppermost label is advanced by rollers 16, 33 and 34 along the cover plate 54 until picked up by the rollers 55 and 56, these rollers advancing the label between the 55 gluing roller 57 and the rollers 62 and 63 where the label receives its coating of adhesive. Each label as it passes through the gluing mechanism is stripped from the gluing roller by the stripping fingers 64.

60

The amount of glue on the gluing roller 57 may be regulated by a doctor plate 66. This plate is pivotally mounted on a rod 67 in the glue pot, a lever 68 being carried by this rod outside of the glue pot, the lower end of this lever being provided with a cam 69. A short rod 70 held against end movement passes through this cam and is provided with two springs 71 and 72, the former holding the cam follower 73 on this rod in engagement with the face of the cam at all times, while the latter prevents retraction of the rod 70 to the right, as viewed in Fig. 1. The outer end of the rod 70 is provided with a dial 74. It will be apparent that by rotating this dial the cam follower 73 will push the lever 68 either to the left or right, thereby to vary the angle that the plate makes with the face of the gluing roller and hence to regulate the amount of glue or paste on the face of this roller.

What I claim is:—

1. A label pasting machine comprising in combination a platform for receiving a stack of labels, racks from which the platform is suspended, a feed roller for feeding labels successively from the top of the stack, spring actuated pinions engaging said racks to elevate the same together with the platform whereby the top of the stack of labels will be maintained in contact with the feed roller at all times, and vertically extending members adjustable laterally with respect to said platform to provide adjustable side guides for the labels on the platform. 100

2. A label pasting machine comprising in combination a platform for receiving a stack of labels, racks from which the platform is suspended, a feed roller above the platform for feeding labels successively from the top of the stack, spring actuated pinions for actuating said racks to elevate the platform to maintain the label stack at all times in contact with the feed roller, and vertically extending members passing through the platform and adjustable laterally with respect thereto affording side guides for the labels on the platform. 110

3. A label pasting machine comprising in combination a platform for receiving a stack of labels, racks from which the platform is suspended, a feed roller above the platform for feeding labels successively from the top of the stack, spring actuated pinions cooperating with said racks for maintaining the label stack in engagement with the feed roller at all times, plates above the rack movable transversely of the label platform, a guide for said plates, and stack guides depending from said plates and passing through slots in the platform and movable with said plates for adjusting the apparatus to labels of different widths. 120
